UNITED STATES PATENT OFFICE.

OLIVER M. RICE, OF BIRMINGHAM, ALABAMA.

AUTOMOBILE DEMOUNTABLE-RIM TOOL.

1,383,856.

Specification of Letters Patent.

Patented July 5, 1921.

Application filed March 6, 1920. Serial No. 363,694.

To all whom it may concern:

Be it known that I, OLIVER M. RICE, a citizen of the United States, residing at Birmingham, in the county of Jefferson and 5 State of Alabama, have invented certain new and useful Improvements in Automobile Demountable-Rim Tools; and I do hereby declare the following to be a full, clear, and exact description of the invention, such 10 as will enable others skilled in the art to which it appertains to make and use the same.

The present invention relates to improvements in tools for contracting and expanding demountable rims, and has for an object 15 to produce a device of this character that will be exceedingly easy to operate and exceedingly strong in construction.

With the foregoing and other objects in 20 view the invention consists in the constructions, combinations and arrangements hereinafter described and pointed out in the claims.

In the accompanying drawings forming a 25 part of this application, and in which similar reference symbols indicate corresponding parts in the several views:

Figure 1 is a plan view of a tool constructed according to the present invention 30 and shown applied to a fragmentary rim.

Fig. 2 is a sectional view taken on the line 2-2 in Fig. 1;

Fig. 3 is a sectional view taken on the line 3-3 in Fig. 2; and

Fig. 4 is a transverse sectional view 35 through the gear mechanism.

Referring more particularly to the drawings, 1 and 2 designate the adjacent ends of the usual demountable rim having the 40 cross cut 3 at which the rim may be expanded or contracted in the usual manner.

The rim is perforated as indicated at 4 and 5 to receive headed pins 6 and 7 projecting from a pair of heads 8 and 9.

The head 9 is carried on the outer end of 45 a threaded shaft 10, which fits loosely for reciprocating movement in a bore 11 provided in a frame 12, which carries the other head 8.

As shown to advantage in Fig. 3, the 50 frame 12 is provided with one or more longitudinally extending slots 13 adapted to receive a pin 14 carried on the threaded shaft 10 for preventing relative turning between the shaft 10 and frame 12, while allowing 55 the free axial movement thereof, a bevel pinion 15 is provided interiorly with spiral

threads whereby it may be received over the threaded shaft 10 and the teeth of which mesh with correspondingly formed teeth on a bevel gear wheel 16. A handle 17 is arranged in operative relation to the gear wheel 16 for rotating the same, whereby similar movement may be communicated to the pinion 15.

As shown in Fig. 3, a sleeve 18 forming 60 part of the frame 12 extends against one side of the pinion 15, while the end of a housing 19 engages the opposite end of said pinion 15 so that the same is fixed against longitudinal travel.

A stud 20 is formed together with the frame 12 or housing 19 and projects at right angles to the axis of the frame and screw shaft 10, and provides a bearing on which the gear wheel 16 may be mounted. The 65 gear wheel 16 and crank handle 17 are preferably rotatably mounted on the stud 20, which is fixed, said handle and gear wheel being splined together. It is obvious that other arrangements, however, may be made 70 if desired.

The housing 19 is also provided with one or more legs 21, two legs being shown in the drawings extending in opposite directions from the lower edges of the housing 19 and having outwardly projecting feet 22 for engaging the ground or a supporting surface whereby the device may be sustained at an elevation thereabove as indicated in Fig. 4.

In use, the handle 17 may be rotated in 75 either direction according as it is desired to expand or contract the rim 1, 2. Rotary motion of the handle 17 is imparted to the gear wheel 16, and consequently to the pinion 15 which is fixed in the housing 19 against axial 80 movement.

The threads on the interior of the pinion 15 turning about in engagement with the spiral threads of the shaft 10, will cause the longitudinal or axial feeding of said shaft 85 in the one or the other direction.

The pin 14 traveling longitudinally in the slot 13 of the frame 12, will keep both the frame and spiral shaft 10 from relative rotation, and the frame and the shaft will 90 therefore be moved apart or together accordingly as the pinion 15 is driven in the one or the other direction.

The pin 14 traveling in the slot 13 will 95 also preserve the heads 8 and 9 in a correct 100 position with their pins 6 and 7 projecting outwardly so as to engage in the perfora-

- tions 4 and 5 in the rim. The feet 21 support the parts above the ground so that no interference may be had with the operation of the gears and their movable parts.
- 5 In actual use the device has been found to give excellent results, as it develops great power with the application of little energy. It will, of course, be understood that the feet 21 may be adjustable if desired.
- 10 It is obvious that those skilled in the art may vary the details of construction and arrangements of parts without departing from the spirit of my invention, and therefore I do not wish to be limited to such features 15 except as may be required by the claims.
- I claim:
1. A tool of the character described comprising a frame having a smooth bore therein and a groove extending longitudinally 20 with said bore, a threaded shaft slidably fitted in said smooth bore and having a projection entering said groove to prevent relative rotation between the shaft and frame, heads carried by the outer ends of said 25 frame and shaft, parts on said heads adapted to engage with a demountable rim, a housing extending about one portion of said frame and having an end wall disposed close to said threaded shaft, a sleeve forming a 30 continuation of said frame closely embracing the threaded shaft and spaced from said end wall, a pinion having spiral interior threads engaged with the threads on said threaded shaft, said pinion disposed between 35 the end of said sleeve and said wall, a stud projecting from said frame at right angles
- to said threaded shaft, a beveled gear wheel on said stud meshing with said pinion, means engageable over said stud and having connection with said gear wheel to rotate 40 the latter, and a pair of feet diverging in opposite directions and provided with angularly disposed toes for supporting the frame and housing, said feet being formed on said frame and housing, substantially as de- 45 scribed.
2. A tool of the character described, comprising a frame having a smooth bore therein, a threaded shaft slidably fitted in said smooth bore, heads carried by the outer ends 50 of said frame and shaft, parts on said heads adapted to engage with a demountable rim, a housing extending about one portion of said frame and having an end wall disposed close to said threaded shaft, a sleeve forming a continuation of said frame closely embracing the threaded shaft and spaced from 55 said end wall, a pinion having spiral interior threads engaged with the threads on said threaded shaft, said pinion disposed between the end of said sleeve and said wall, a stud projecting from said frame, a beveled gear wheel on said stud meshing with said pinion, means engageable over said stud and having connection with said gear wheel 60 to rotate the latter, and feet diverging in opposite directions for supporting the frame and housing, said feet being formed on said frame and housing, substantially as de- 65 scribed.

OLIVER M. RICE.
